UNITED STATES PATENT OFFICE.

PHILIP S. GIROUX, OF WARREN, MASSACHUSETTS.

SPINNING MACHINE.

Application filed December 29, 1925. Serial No. 78,240.

This invention refers to cotton yarn machinery and more particularly to an attachment for a spinning machine to produce an auxiliary control of the motion of the spindles and bobbins and the threads or yarns used in connection therewith.

Some of the main objects of this invention are to provide an auxiliary bobbin control that will definitely place the "bunch" on the bobbin in a predetermined position thereon; that will control the size or quantity of the bunch according to a predetermined setting; that will have arrangements for adjusting the movement of this auxiliary bobbin control; that may be attached to standard spinning frames with facility and without excessive drilling or displacement of parts; that will function definitely with and in conjunction with other parts 20 of the spinning machine and the mechanism of the latter; and many other objects that will become apparent as the invention is more fully set forth.

In the present types of spinning machines, 25 the winding of the yarn or thread on the bobbin produces a "bunch" of thread or yarn located more or less indefinitely. This indefinite location causes difficulties in the operation of the machine by reason of the 30 breakage that results and the lumping up of thread or yarn towards the middle portion of the bobbin. In addition, wastage occurs on the bobbin by reason of the premature breaking of the thread or yarn, the 35 excessive amount of thread left on the bobbin at the time, and the various uncertainties that enter into the situation. On one bobbin the wastage at one time may be twenty yards, and then again on the next 40 operation the bobbin in the same position may waste double the amount, and so on in consequent operation the amounts may vary preventing any definite predetermination of this waste. As thousands of bobbins may be 45 used in a mill having spinning machines wasting thread and yarn in this manner, the consequent result affects materially the cost of operation and manufacture.

In this invention, the wastage is reduced, 50 the amount of wastage is predetermined and adjusted for, and the general operation of the spinning machine is made smoother and more economical. The device is simple in construction and takes up little room on the machine, and such room as it does use, is in an inconspicuous location where it is out of

the way of the operator's movements and the general mechanism of the spinning machine. It avoids the mutilation or changing of existing parts of the spinning machine. It 60 has features of adjustment that permit its functioning in the spinning machine to the greatest extent of adaptability.

In the drawings which illustrate by way of example, an embodiment of this invention:

Figure 1 represents a side view of an auxiliary bobbin control embodying this invention.

Figure 2 is a view of a bobbin with the 70 thread or yarn thereon formed with a "bunch" arranged with this invention.

Figure 3 is an end view of the auxiliary bobbin control shown in place attached to the cam mechanism.

Figure 4 is a view of the auxiliary bobbin control positioned after it has run its stroke and before being returned to contact or operating position.

Figure 5 is a diagrammatic view showing 80 the parts controlled under the operation of this invention.

Figure 6 is a perspective detail of the bobbin shelf.

Figure 7 is a diagrammatic view of the 85 control device with its segmental gear leaving the propelling pinion, just before the position indicated in Figure 4 is attained.

Similar reference characters refer to similar parts throughout the drawings.

In the construction shown in the drawings, 1 is a building lever of a conventional form of spinning machine, which building lever controls the movement of the thread on the bobbin in accordance with a cam 2 that is attached to the frame of the machine and which makes contact with its roller or ball 3 that is on this lever. The general movement of the parts in the conventional spinning machine is so well known as not to require further description in detail. Attached to the lever 1 by the bolt 4 that holds the ball 3 in place, is the arm 5 of the auxiliary bobbin control, a hole 6 being provided in the latter for this bolt to pass through and secure the arm as indicated in the drawings. The upper portion of this arm is provided with a slot 7 to enable a bolt 8 to be vertically adjustable therein when the arm is in place, and thus make its gear-segmental parts 9 come into suitable contact with a pinion gear 10 secured on the central portion of the cam

2 in a rigid manner so as to operate therewith. This pinion is mounted on a base 11 that is secured to the cam 2 by cap screws 12. The pinion and segmental gear correspond 5 and are designed in sizes to be suitable for their respective and cooperative functions.

The building lever is of conventional form having suitable counterweight to keep its rear position raised towards the cam surface, 10 and has a chain 13 with the segmental arm 14 adapted to be operated in an arc and transmit a vertical movement to the bobbin shelf 15 through roller or ball 16 and standard 17 in the usual conventional manner.

15 The raising of the shelf controls the movement with respect to the bobbin and yarn or thread filling on. This filling will vary so that the bunch may take practically any position on the bobbin, and is erratic because 20 of the uncertain relation of the bobbin with respect to the movement of the building cam in its conventional action.

When the auxiliary bobbin control is placed on the machine as indicated in the 25 drawings, its action is such that the segmental gear is brought into contact with the pinion and indirectly cooperates with the cam 2, at its beginning position and when the building lever is raised. In other words the lever, 30 the cam, and the auxiliary bobbin control are set at a certain position, which corresponds to the starting of the bobbin filling process. The segmental gear being in contact serves to keep the cam and its roller or ball out of contact until the number of teeth 35 on the segmental gear in use are "run off." During this run-off the thread or yarn makes the bunch on the bobbin and at the lower end of the bobbin. The amount of the bunch 40 is determined by the movement of the segmental gear, which in turn through the other mechanism of the spinning machine influences the filling process. After the segmental gear has completed its arc stroke, it 45 progresses until the indentation is reached, at which point the indentation 45 moves up against the pinion gear and allows the building lever and the arm 5 to rise also. As the building lever rises under the action of gravity 50 on its counterweight, the ball 3 makes contact with the cam 2 and for the rest of the filling process the regular action of the spinning machine takes place.

When the bobbin is filled it is removed 55 and another put in its place, the bobbin shelf is moved through a special mechanism operated by the foot, and the building lever is so depressed that

60 In Figure 2, the bobbin is indicated at 19 with the yarn shown at 20 and the bunch at 21 near the bottom.

That the segmental gear is lowered out of its indentation portion from contact with the pinion. The segmental gear is over-weighted on the portion 46 that helps to

form the indentation, and in addition has an adjustable stop 47. The segmental gear being overweighted falls clockwise over until limited in its movement by the stop striking the side of the arm 5. This position places 70 the teeth of segmental gear under the teeth of the pinion gear automatically, so that when the building lever is released by the foot, it rises and places these two gears into a predetermined position of contact, and 75 ready to proceed to control the filling process of the bobbin.

The adjustable stop 47 has a series of positions 18 to provide for a control of the arc of movement of the segmental gear, thus enabling the bunching process to be made 80 small or large as the case may need.

The construction of this segmental gear is such that its gear teeth may be interchangeably positioned against the pinion gear, the 85 manner of doing so being by replacing this portion of the control after reversing the segmental gear faces. This feature permits a quick change in case of an urgent need of an emergency gear on the segment. The 90 two segments are provided with means for attaching the overweight and for adjustability of movement.

It should be noted that the only constructional change in the conventional form of 95 spinning machine required, is the drilling of two small holes for attaching the pinion gear to the cam, a matter of little difficulty, and which does not affect the spinning machine in any way in case they should not be utilized at any time.

While but one form of the invention is shown in the drawings it is not desired to 100 limit this application for patent to that particular form or in any way, than limited by the prior art, as other forms could be made that would use the same principles and come within the scope of the appended 105 claim.

Having thus described the invention, what 110 is claimed is:

An auxiliary control comprising in combination, an arm attachable to the building lever of a spinning machine, a double segmental member movable on the upper portion of the arm having means for adjustably positioning it on the arm and its movement thereon, one of said segmental parts having gear thereon, and another portion weighted to normally position the whole member in a predetermined position, a gear moveable with the cam mechanism of the spinning machine, adapted to engage with segmental gear portion, and during such engagement to directly disengage the said lever from the cam mechanism, until a certain period of the spinning has transpired.

In testimony whereof I hereunto affix my signature.

PHILIP S. GIROUX.
